UNITED STATES PATENT OFFICE.

GUSTAF SYLVAN, JOHANNES B. SYLVAN, AND EMIL WILHELM SYLVAN, OF COLUMBIA, SOUTH CAROLINA.

CLOCK-MOVEMENT.

No. 888,271.

Specification of Letters Patent.

Patented May 19, 1908.

Application filed September 13, 1907. Serial No. 392,726.

To all whom it may concern:

Be it known that we, GUSTAF SYLVAN, JOHANNES B. SYLVAN, and EMIL WILHELM SYLVAN, citizens of the United States, residing at Columbia, in the county of Richland and State of South Carolina, have invented a new and useful Improvement in Clock-Movements, of which the following is a specification.

10 The object of this invention is to provide means for securing a more uniform transmission of power from the main spring of a clock, or watch, to its escapement, to render the same more accurate in its time keeping values. It is well known that when the main spring is wound up to its maximum tension, it transmits its power more energetically than when it is relaxed and nearly run down.

15 The invention is designed to overcome this irregularity and to render the transmission of power to the escapement substantially uniform throughout the entire range of the unwinding movement of the main spring, and to that end it has already been proposed to 20 interpose in the train of gears between the main spring and the escapement, a secondary intermediate spring which is wound up in an automatic manner by the main spring at regular intervals and which intermediate 25 spring transmits its tension to the escapement, so that the escapement is always actuated by this intermediate spring.

Our invention consists in the novel construction and arrangement of trip and locking devices for bringing into action the main spring to wind up the intermediate spring, and to stop the main spring's action after it has thus wound up the intermediate spring.

Figure 1 is a side elevation of so much of a 20 clock movement as is necessary to illustrate our invention, the covering plate of the attachment being removed. Fig. 2 is a view of the same looking edgewise the gear wheels and showing the cover plate applied. Fig. 3 is an enlarged section taken through the intermediate clock spring and its immediate 25 connections. Fig. 4 is a detail in perspective of the trip and lock devices detached. Fig. 5 is a side view and Fig. 6 an edge view of a 30 modified form of the invention and Figs. 7 and 8 are details of the same.

In the drawing, Figs. 1 and 2, A represents the front and A' the back plate of the frame of the clock movement, between which the

various gears of an ordinary clock movement 55 are contained.

A' is a supplemental front plate, shown in Fig. 2, but removed in Fig. 1, and between which and the usual front plate A the principal parts of our attachment are contained. 60

B is the usual main spring with barrel, winding shaft, ratchet and pawl. To this barrel, see Fig. 2, is attached the main drive wheel 1 whose teeth mesh with and turn the pinion 2. Ordinarily this pinion 2 transmits its power through the gear wheels 3, 4, 5, 6 and 7 to the escapement C. In the present invention, however, the pinion 2 is not directly connected to the gear wheel 3, but only indirectly through the interposition of 65 the intermediate spring which is wound up intermittently by the main spring B and which intermediate spring transmits its derived power through the train of gears 3, 4, 5, 6 and 7 to the escapement, so that the 70 clock time-mechanism is driven through the intermediate spring instead of by the main spring direct, as hereafter more fully described.

The intermediate spring and its accessories are contained between the frame plates A and A', in Fig. 2, and the principal parts of it are shown detached in Fig. 3—in which 75 2 is the same pinion shown at 2 in Fig. 2 which is driven by the main gear 1 on the 80 spring barrel. This pinion 2, Fig. 3, is rigidly attached to a shaft a which on its outer end has a squared portion a' fitting the squared hole of a gear wheel D to which is rigidly connected a spring barrel D' containing 85 the intermediate coil spring E which is of sufficient length and tension to run the clock through the predetermined intervals of its winding by the main spring. One end e² of this spring is attached to the barrel D' 90 and the other end e³ is attached to the hub of the gear wheel 3 which gear wheel is loose on the shaft a. One of the outer convolutions of this intermediate coil spring E is caught by a split or bifurcated pin b² attached at right angles to a trip lever b on the outer side of gear wheel D. This split pin 95 plays in a slot d', Figs. 3 and 4, in the side of the spring barrel and has a motion to or from the center according as the spring is wound 100 up and restricted or relaxed and expanded.

As seen in Fig. 3 the spring E is wound up and constricted and the split pin b² is near-

est to the center of the shaft a and in the inner end of the slot d' , but when this spring is expanded and run down, the pin b^2 is forced by the outer convolution of the spring 5 to go to the outer end of the slot d' . This movement of the pin b^2 to or from the center is made to effect the starting and stopping of the intermittent winding of the intermediate spring E as follows: The trip lever b is 10 bowed or elbow-shaped, as seen in Fig. 1, and when its pin b^2 is at the inner position, as shown in Figs. 1, 3 and 4, (the intermediate spring E being wound up) the outer end of lever b abuts against a locking lever d , as in 15 Figs. 1 and 4. The lever d is pressed against lever b by a spring d and as the wheel D is strained in the direction of the arrow by the pressure of the main spring through pinion 2 and shaft a , it will be seen that the lever d is 20 tilted on its pivot against spring d^3 . In this position of parts the intermediate spring E (under tension) is turning the loose gear wheel 3, Fig. 3, and is actuating the clock gears 4, 25 5, 6, 7, 8 leading to the escapement. When, however, the spring E runs down, after the predetermined period, the expansion of the spring carries the split pin b^2 to the outermost portion, and in doing so, see Fig. 1 30 throws the trip end b' (which is resting against lock lever d) inwardly and off the lock lever, and, the gear wheel D, being now free to turn in the direction of the arrow from the power of the main spring, turns a 35 complete revolution and in doing so winds up the intermediate spring, and the lever b again strikes lock lever d and stops the further movement of the main spring. To hold the wheel D against back movement a detent e is held against its teeth by spring e' . 40 If there were nothing to prevent it, the powerful strength of the main spring would wind up the intermediate spring with a jerk and a sharp impact. To prevent this the gear wheel D has its teeth engaging a pinion 45 8, Fig. 1, on the same shaft with gear wheel 9 and gear wheel 9 turns the pinion 10 of a fly fan 11. This fly fan is held by the upper end of the lock bar d , as seen in Fig. 1, but whenever the lock lever d is tilted by its spring d^3 50 (after lever b has tripped it) this same movement releases the fly fan and then two actions occur simultaneously. One of these actions is the winding of the intermediate spring by the main spring and the other is 55 the retarding of the winding-up movement by the rapid rotation of the fly fan, so that all shocks and jars are avoided. As a modification of this retarding mechanism, we may employ the means shown in Figs. 5, 6, 7 and 60 8. In this modification we use, in the place of the fly fan, a vibrating escapement such as is used to vibrate the hammer of an alarm clock. The shaft a with a square end a' , pinion 2, intermediate spring E, barrel D', gear wheel D and split pin b^2 are exactly the same 65 as in Figs. 1 to 4. The changes are as follows. The gear wheel D has pivoted to it a pawl b a which bears the split pin b^2 passing through the slot d' and engaging the outer convolution of the spring E as seen in Fig. 8. 70 A loose arm d a vibrates on the hub of gear wheel D and has a locking tooth y adapted to be engaged by the pawl b a when spring E is completely wound up. The loose arm d a has a pin x that stops against a bent wire 15 fixed 75 to a pallet escapement 14 vibrating on the teeth of wheel 13. This wheel is on the same shaft with pinion 12 which latter is engaged by the teeth of wheel D, so that when wheel D turns, the pallet escapement 14 vibrates as in the hammer mechanism of an alarm clock. When spring E is wound up, pawl b a strikes lug y and holds the stop arm d a and pin x against the escapement wire 15, but when spring E is expanded and run 80 down, pawl b a leaves lug y and wheel D can then turn from the action of the main spring to wind up the intermediate spring, as before described, and arm d a being released from bearing against wire 15 the escapement 85 produces the same retarding effect that the fly fan did in the first described form, with the difference that the fly fan is nearly noiseless, while the vibrating pallet produces a buzzing sound. When the wheel D makes 90 its complete revolution, (in winding up the intermediate spring) the pawl b a , being carried toward the center by the constricted spring E, strikes against lug y and stops the winding action leaving the main spring at 95 rest until the next winding movement and the pin x pressing against wire 15 stops the escapement. 100

In making use of our invention, we do not confine it to clocks and watches, but may use 105 it in the transmission gears of all kinds of spring motors, it being especially useful for such spring motors as are employed in phonograph and graphophone machines, or any other mechanism which requires to be run at 110 a uniform rate of speed.

We claim

1. A spring motor transmission gear for clocks &c., comprising a main spring with winding mechanism, an escapement and gears connecting the main spring and escapement, said gears having interposed in their train an intermediate spring, arranged to be wound up at intervals by the main spring and to transmit its power directly to the escapement, locking devices for holding the main spring inactive during the action of the intermediate spring and a trip device for releasing the locking device when the intermediate spring becomes relaxed and for bringing the main spring into winding action again, said trip device consisting of a stop bar connected to one of the outer convolutions of the intermediate spring and movable to or from the center of the same. 115 120 125 130

2. In a spring motor transmission gear for
clocks &c., the combination of a winding
shaft bearing a rigid pinion and a squared
end, a rigidly connected gear wheel and barrel
5 on said squared shaft, a coil spring arranged
within the barrel and having one end at-
tached to the same, a loose gear wheel on said
shaft attached to the other end of the spring,
a trip lever having a pin acted upon by the
10 expansion and contraction of the coils of the
spring and a trip device for the trip lever.

3. In a spring motor transmission gear for
clocks &c., the combination of a winding shaft
bearing a rigid pinion and a squared end a
15 rigidly connected gear wheel and barrel on
said squared shaft, a coil spring arranged
within the barrel and having one end at-
tached to the same, a loose gear wheel on said
shaft attached to the other end of the spring,
20 a trip lever having a pin acted upon by the
expansion and contraction of the coils of the
spring, a stop device for the trip lever, and a
retarding device for the winding shaft and
gear wheel.

25 4. In a motor transmission gear for clocks
&c., the combination with the prime motor
and escapement gears; of an intermediate
spring, a gear wheel attached to the inner end
of the same, a gear wheel parallel with the
30 first named and having a housing attached to
the outer end of the intermediate spring, a

central shaft rigidly connected to the housing
gear, a lever on the outside of the housing
gear and parallel with it and having a pin op-
erated upon by the outer coil of the interme- 35
diate spring, a movable stop device for said
lever and a speed retarding device held by
said stop device.

5. A transmission gear for clocks &c., com-
prising a prime motor, an escapement and 40
gears connecting the prime motor and escape-
ment, said gears having interposed in their
train an intermediate spring, arranged to be
wound up at intervals by the prime motor
and to transmit its power directly to the es- 45
capement, locking devices for holding the
prime motor inactive during the action of the
intermediate spring and a trip device for re-
leasing the locking device when the interme-
diate spring becomes relaxed and for bring- 50
ing the prime motor into winding action
again, said trip device consisting of a stop
bar connected to one of the outer convolu-
tions of the intermediate spring and movable
to and from the center of the same.
